BOILER CLEANER

Norman L. Snow, New Canaan, Conn., assignor
to Diamond Power Specialty Corporation,
Detroit, Mich., a corporation of Michigan

Application February 11, 1924, Serial No. 692,094
Renewed February 11, 1932

5 Claims. (Cl. 122—392)

This invention relates to boiler cleaners and among the objects of the invention are to provide an improved apparatus for and method of cleaning boilers.

5 In the drawings, in which I illustrate one embodiment of my invention:

Figure 1 is a side elevational view partly in section showing one form of my invention applied to a boiler;

10 Figure 2 is an enlarged elevational view of part of the boiler cleaning mechanism shown in Fig. 1;

Figure 3 is an elevational view taken at right angles to Fig. 2.

15 Describing first in detail the general arrangement illustrated in Fig. 1, A designates a boiler, which in the particular construction shown is of the Stirling type, having upper drums B connected to the lower drum B' by means of boiler tubes C. For cleaning the soot, slag or the like from off the boiler tubes there is preferably employed a blower pipe or cleaning element D having a plurality of nozzles D' through which jets of cleaning fluid such as steam or air are discharged to clean the soot or other deposits or accumulations from the boiler tubes C.

20 A steam connection to the blower pipe is provided by means of the vertical pipe or header E connected to the steam space of the boiler, which connection is controlled by a main valve E', there being a drain valve E² at the lower end of this header. A branch supply pipe E³ is connected to the head E⁴ in which the blower pipe D is swivelled. The supply of steam from the pipe E³ to the blower pipe D is also controlled by valve F which is actuated by a suitable mechanism such as the cam F' adjustably fixed on the front face of gear 15 by brackets 15' for depressing trigger 10, the latter being pivotally supported on bolt 11. This trigger is engageable with the valve stem 12 of the valve F for actuating the same so as to have the valve open when the nozzles D' are pointed in certain predetermined directions. The actuation of the valve F and the rotation of the blower pipe D are both, in the particular construction shown, produced by pulling the chain F², so as to rotate sheave 13 and pinion 14, the latter meshing with the gear 15. Rotation of this gear causes rotation of the cam F' fixed therewith, the cam depressing trigger 10 to unseat valve F. If desired, the valve F could be actuated from any other suitable power applying means.

25 In addition to the deposit of soot on the boiler tubes, there is also formed in many cases a slag

which is very hard to remove. The removal of this slag from the tubes is aided, in the present construction, by an arrangement for adding to, or substituting for, the regular fluid used in the soot blower, some other ingredient which has a 60 more powerful action on the slag than does the regular cleaning fluid. The blowing fluid may be steam or air and the material added to or substituted therefor might be water or some chemical which rapidly attacks the slag such as sodium silicate solution. These materials have been found to be very effective in the removal of slag when added to the regular cleaning fluid such as steam or air. Applicant has provided a 65 construction wherein water, or whatever slag removing solution may be found most desirable, is added to the regular cleaning fluid in any desired proportions. The proportion of the liquid added, may be varied in accordance with the character of the deposits to be removed. Thus, starting with saturated steam, such as would be available at the boiler drum in Figure 1, liquid might be introduced until the cleaning fluid possessed the characteristics of very wet steam, 70 or even up to the point where the fluid was practically all water.

75 This additional material could be introduced into the supply line to the soot blower in various ways but in the illustrative construction shown it is introduced as follows: Leading into the head E⁴ above the steam control valve F is a pipe G connected to a vertical header G' which at its lower end has a connection G² leading to the water drum B' which connection is controlled by valve G³. The header G' is also connected to a pump H by means of a pipe line H' controlled by a valve H² which pump in turn is connected to a supply tank H³ which contains a solution of sodium silicate or other desired substance. The connection between the pipe G and the head E⁴ is controlled by a valve I which in turn is actuated by a cam J likewise adjustably fixed to the gear 15 on the face thereof opposite to that carrying the cam F'. This cam depresses the valve stem I' of the valve I by means of a trigger J' also pivotally supported on the bolt 11 and provided with the shoulder I² offset for engagement with the valve stem I'. By properly setting the cams J and F' rotatively 90 in their brackets 15' the exact time at which the fluid through the pipe G is admitted to the blower pipe can be properly governed.

95 One method of operation would be that the steam valve F is opened first so that the velocity 100 of the steam from the steam connection E³ 105

110

would pick up the liquid as it is admitted after the liquid valve I is open. Another advantage in first introducing steam has to do with the rate at which the blower element is cooled when 5 cleaning fluid is admitted thereto. At the point where slag formations ordinarily occur, temperatures are very high and a blower element located at such a point would be subjected to quite high temperatures. If water were suddenly introduced into an element so located, 10 the damage or warpage would be very great because of the very large temperature change. By first introducing the steam, followed by the mixture of steam and liquid, the temperature change 15 would be accomplished gradually and with greatly reduced shock to the blower element. A further advantage of the primary introduction of steam lies in the possibility of first blowing off with the steam any loose deposits, leaving the 20 highly adherent slaggy deposits to be removed by the mixture of steam and the additional cleaning fluid. The additional liquid might be either the water from the boiler through the pipe G² when the valve G³ is opened, which be- 25 cause of the pressure in the boiler would be forced up through the header G' to the valve I, or it might be the liquid from the tank H³ forced up through the header G' when the valve H² is opened and the pump H running or it might be both when the valves G³ and H² were open.

As shown in Fig. 3 the head or gooseneck E⁴ is provided with an aperture K through which is inserted a removable orifice plate L having an orifice L' of the desired cross-section. This plate is secured in position by means of a plate M clamped to the head E⁴ by means of set screws N. By this novel arrangement the interior passages of the gooseneck or head E⁴ can be made of any desired size and the passage restricted to the desired diameter or cross-sectional opening by means of the orifice plate which can be readily removed and a different one substituted if desired. It will be noted that 45 the removable orifice plate K is located beyond the valves F and I. While I have shown this removable orifice as located in the head E⁴ it of course could be placed in the rotating pipe D or in other desired positions in advance of 50 the discharge openings or nozzles D'.

While I have shown and described one illustrative construction in which there is a combination of two liquid supply sources with one steam supply source, it is understood that the 55 invention is not limited to such combination as a single source of liquid supply or any number, or a source of cleaning fluid other than steam, or a cleaning substance other than a liquid, might be employed and various other changes 60 both in the construction and method of operation could be made without departing from the scope of my invention in its broader aspects.

For the sake of convenience the invention has 65 been described as being embodied in a device for

cleaning parts of a boiler. It will be apparent, however, that the invention may be incorporated in devices for cleaning similar types of apparatuses, and it is to be therefore understood that the term "boiler" wherever used in the specification and claims is to be construed as meaning a fluid heater or heat transfer apparatus of any character, while the term "boiler cleaner" is to be construed as meaning a cleaner for any such apparatus.

What I claim as my invention is:

1. In a boiler cleaner for removing slag, a rotatable blower element provided with a nozzle adapted to discharge a jet of fluid adjacent parts of the boiler to be cleaned of slag, means for imparting rotation to said nozzle, a valve controlled cleaning fluid supply pipe communicating with said blower element, a second valve controlled pipe for conducting a second cleaning substance to said blower element, and means actuated by said rotating means for controlling the movement of said valves in a predetermined relative timed relation. 80 85

2. In a boiler cleaner, a blower element, a plurality of pipes for supplying cleaning fluids to said blower element, a valve associated with each pipe for controlling the flow of cleaning fluid from its respective pipe to the blower element, and means automatically operating to actuate said valves according to a predetermined desired sequence to admit cleaning fluid from said pipes to said blower element according to a predetermined desired sequence. 90 95

3. In a boiler cleaner, the combination with a blower element, of a pair of pipes for supplying cleaning fluids to said blower element, a valve associated with each pipe for controlling the flow of cleaning fluid from its respective pipe to the blower element, and means automatically operating to successively actuate said valves to supply said cleaning fluids to said blower element according to a predetermined desired sequence. 100 105

4. In combination, a blower element, a plurality of sources of supply of cleaning fluid under pressure, a control means operatively associated with each source of supply of cleaning fluid for controlling the flow of cleaning fluid therefrom to the blower element, and means operating to actuate said control means according to a predetermined desired sequence whereby cleaning fluids are admitted to said blower element from said sources of supply according to a desired sequence. 110 115 120 125

5. In combination, a blower element, means for supplying a cleaning fluid to said blower element, and means operating to supply a second cleaning fluid to said blower element in a predetermined sequence with respect to the supply of said first mentioned cleaning fluid, said last mentioned means being operable irrespective of the supply of said first mentioned cleaning fluid to the blower element. 130 135 140
